US0D1106112S

(12) **United States Design Patent** (10) **Patent No.:** **US D1,106,112 S**
(45) **Date of Patent:** **** Dec. 16, 2025**

(54) **HEADPHONES**

(71) Applicant: **Bang & Olufsen A/S**, Struer (DK)

(72) Inventors: **Ryoji Takahashi**, København (DK); **Romina Rumi**, Lyngby (DK); **Miklu Silvanto**, København Ø (DK); **Tiina Karjalainen Kierysch**, Malmö (SE); **Alvin Tham Hiok Cheng**, Yishun (SG); **Magnus Søgaard Magnussen**, Taastrup (DK); **Gabriel Kure**, Helsingør (DK)

(73) Assignee: **Bang & Olufsen A/S**, Struer (DK)

(**) Term: **15 Years**

(21) Appl. No.: **29/925,040**

(22) Filed: **Jan. 22, 2024**

(30) **Foreign Application Priority Data**

CLAIM

The ornamental design for headphones, as shown and described.

DESCRIPTION

FIG. 1 is a top, back, left-side perspective view of headphones showing our new design;

FIG. 2 is a top, front, right-side perspective view thereof;

FIG. 3 is a back view thereof;

FIG. 4 is a front view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the headphones that form no part of the claimed design.

1 Claim, 8 Drawing Sheets
